WILLIAM F. HANSON, OF SAN FRANCISCO, CALIFORNIA

CLOCK FRAME

1,415,636.

Specification of Letters Patent

Patented May 9, 1922

Application filed May 8, 1919. Serial No. 295,653.

To all whom it may concern:

Be it known that I, WILLIAM F. HANSON, a citizen of the United States, and a resident of the city and county of San Francisco and State of California, have invented a new and useful Clock Frame, of which the following is a specification.

My invention relates to clock frames and means for mounting spring arbors therein. An object of the invention is to provide a clock frame and mounting for the spring arbors such that the spring and arbor are readily disengaged from the frame without disturbing the rest of the mechanism.

15 Another object of the invention is to provide a clock frame in which one of the posts holding the parts of the frame together, and to which the end of the spring is attached, is releasable from the frame without dis-
20 turbing other parts.

The invention possesses other objects and features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I may adopt variations of the preferred form within the scope of my invention as set forth in the claims.

Referring to the drawings:

Figure 1 is a plan view of a portion of a
35 clock frame embodying my invention. Figure 2 is a vertical section through a portion
of a clock embodying my invention. The
planes of section are indicated by the line
2-2 of Figure 1. Figures 3 and 4 are per-
40 spective views showing details of the con-
struction. Figure 5 is a plan view of a por-
tion of a clock frame and mounting embody-
ing a modified form of my invention. Fig-
ure 6 is a vertical sectional view taken in the
45 plane indicated by line 6-6 of Figure 5.
Figure 7 is a plan view of a portion of a
clock frame and mounting embodying an-
other modification of my invention. Figure
8 is a vertical sectional view of the structure
50 shown in Figure 7 and taken in the plane
indicated by line 8-8 of that figure.

As clocks are usually constructed it is necessary to disassemble the entire structure to remove any given shaft or arbor. It is broadly an object of my invention to provide a structure, such that the main or alarm

spring arbor for instance, may be removed and reassembled with a new spring without disturbing the other mechanism of the clock. Since a spring is attached not only to its arbor or shaft but also to one of the corner posts of the frame, my invention covers means for releasably mounting both the spring arbor and the corner post. 60

The corner post 2, one end of which is shown in Figure 4 is formed to provide a cylindrical neck 3 connecting the head 4 with the body of the post. The neck is flattened on opposite sides, as at 6, to permit its insertion into the socket 7, formed in the frame 8, through the slot 9 connecting the socket with the edge of the frame. Both ends of the post are alike and so are the rear and front frames 8 and 11, respectively. The post is pushed through the slots into the sockets and then turned 90° to tightly seat the post in the frames. The frame 8 is formed with a socket 12 in which the bushing 13 Figure 3 is adapted to be seated to form a bearing for and position the arbor 14 upon which the spring 16 is mounted. The socket 12 comprises a circular aperture and is connected to the edge of the plate by a slot 17, the width of which is greater than the diameter of that portion of the arbor 14 which passes through it when the parts are assembled, and spans preferably about one-sixth of the circumference of the aperture. Two other slots 18 of the same width as slot 17 are extended from the aperture into the frame and spaced 120° from the slot 17, thus providing three evenly spaced segments 19 which are preferably raised somewhat above the plane of the surrounding frame as shown best in Figure 2. The bushing 13 is cylindrical in form having a diameter such as to tightly seat within the segments 19. A complete annular flange 21 forms a head for the bushing, and at the lower end are formed three evenly spaced segmental flanges 22 of a size to permit passing through the slots 17 and 18. The bushing is seated in the socket by inserting the flanges 22 through the slots and turning the bushing through about 60° or until the stop pin 23 engages the recess 24 formed at the inner end of the slot 17 in one of the segments 19. The segmental flanges are then securely held under the segments 19 flush with the inner face of the frame, the tight frictional engagement of the bushing with the segments preventing accidental turning of the bushing. The front frame 11 is also pro-

vided with a similar bushing 13. The arbor 14 which carries the spring 16 and the usual driving gear 27 is journaled in the bushings 13, and is provided with a threaded end 28 to which is affixed the winding key in the usual manner.

Assuming that the spring 16 is to be replaced, the parts are disassembled as follows: The winding key is first removed and the 10 bushings are turned about 60°, by means of a suitable tool engaging the holes 29, to permit them to be lifted out of their sockets and slipped off of the end of the arbor. The arbor, together with the spring, is then 15 moved transversely through the slots 17. The post 2 is turned 90° and disengaged from the frames by transverse movement through the slots 9. The spring may now be readily detached from both arbor and post, 20 a new spring placed thereon and the parts reassembled, no other portions of the clock mechanism being disturbed. If desired the front frame 11 is formed with a plain bearing for the arbor and the slot 17 is formed 25 wider than the body of the arbor. The arbor is then disengaged by removing the bushing in the rear frame, moving the arbor axially out of its bearing in the front frame and then transversely through the slot.

30 In the construction shown in Figures 5 and 6, the bushings 31 which form bearings for the arbor 32 are threaded below the head 33 in which spanner wrench sockets 34 are formed. The bushings screw into suitably 35 threaded apertures in the frames 35, the apertures being connected by slots 36 with the edges of the frames. The slots are wide enough to permit the transverse movement of the arbor therethrough after turning out 40 the bushings, and are curved concentric with the axis of the post 37. The construction of post 37 and arbor 32 is the same as that of post 2 and arbor 14 except that each is formed to receive links 38 on the ends. 45 These links form additional bearing surface for the arbor, and when the arbor is swung outwardly from the frames, the links pivot on the post. With the arbor in place 50 of the plates. The links thus comprise a pivoted frame for holding the arbor, and the bushings position the frame and arbor and form bearings for the latter.

To remove the spring, the bushings are 55 unscrewed and the arbor swung free of the frames 35. The post 37 is then turned 90° and slipped out of its sockets, when the links and spring 16 may be taken off.

In Figures 7 and 8, I have shown a construction in which the bushings 41 are held 60 friction tight at one end in a bar 42. The other end of the bushings are adapted to seat snugly in suitably spaced and sized apertures 44 in the frame 43. One of the bushings is for the main spring arbor and the

other for the alarm spring arbor, and with the bushings seated in the frame, the bar is secured thereto by a screw 46. Each of the apertures 44 is connected to the edge of the frame by a slot 47, through which the arbors 70 may be removed when the bushings are taken off by lifting the bar. The structure of the posts 2, and the associated frame structure is the same as that already described. If desired a similar bar and bushings may be 75 used on the front frame, or that frame may provide plain bearings for the arbors. In this case the arbors are lifted axially to free the ends from the plain bearings and then disengaged from the rear frame by trans- 80 verse movement through the slots.

I claim:

1. In a clock, a frame formed with an aperture and a slot connecting the aperture to the edge of the frame, an arbor adapted to be moved transversely through said slot, and a bearing bushing for said arbor seating in said aperture, said aperture being formed with inwardly extending segments and said bushing with segmental flanges whereby said 90 bushing is movable axially into said aperture and turnable therein to align the flanges with the segments.

2. In a clock, a frame formed with an aperture and a slot connecting the aperture to the edge of the frame, an arbor adapted to be moved transversely through said slot, a bearing bushing for said arbor seating in said aperture, said aperture being formed with inwardly extending segments and said 100 bushing with segmental flanges whereby said bushing is movable axially into said aperture and turnable therein to align the flanges with the segments, and means for limiting the 105 turning movement of said bushing in said aperture.

3. In a clock, a front and rear frame each formed with two apertures each aperture being connected by a slot with the edge of the frame, a spring arbor adapted to be 110 moved transversely through one pair of said slots, a spring secured to said arbor, bearing bushings for said arbor seating in the associated apertures, and a post to which the end of said spring is attached and adapted 115 to be moved transversely through the other pair of said slots to seat in the associated aperture without longitudinal movement.

4. In a clock, a frame formed with an aperture and a slot connecting the aperture 120 to the edge of the frame, an arbor adapted to be moved transversely through said slot, and a bearing bushing for said arbor seating in said aperture, said aperture being formed with inwardly extending segments 125 and said bushing with segmental flanges at one end and a flange at the opposite end whereby said bushing is movable axially into said aperture and turnable therein to engage said segments between the segmental flanges 130

and the flange at the opposite end of the bushing.

5. In a clock, a front and rear frame each formed with an aperture therein and a slot connecting the aperture with the edge of the frame, and a post for connecting said frames having a flattened neck at each end whereby the post is adapted to be moved transversely through said slots and rotated in said apertures to secure it in said frames.

6. In a clock, a front and rear frame formed with aligned apertures and slots connecting the apertures with the edges of the frames, a post having a flattened neck at each end whereby the post is adapted to be moved transversely through the slots and ro-

tated in said apertures to secure it in said frames, one of said frames being formed with a second aperture and a slot connecting the second aperture to the edge of the frame, 20 an arbor adapted to be moved transversely through said slot, a bearing bushing for said arbor seating in said aperture and a spring on said arbor and connected at one end to said post.

In testimony whereof, I have hereunto set my hand at San Francisco, California, this 30th day of April, 1919.

WILLIAM F. HANSON.
